UNITED STATES PATENT OFFICE.

CHARLES J. TRAUB, OF CINCINNATI, OHIO.

GRATE.

1,410,628.

Specification of Letters Patent. Patented Mar. 28, 1922.

Application filed April 1, 1920. Serial No. 370,497.

To all whom it may concern:

Be it known that I, CHARLES J. TRAUB, a citizen of the United States, residing at Cincinnati, in the county of Hamilton and State 5 of Ohio, have invented certain new and useful Improvements in Grates, of which the following is a specification.

My invention relates to improvements in stoves or furnaces; and its objects are to provide for burning either solid or fluid fuel in the same combustion space, to permit the change of fuels to be made very conveniently, and to burn either kind of fuel efficiently, without hindrance due to the presence in the 15 combustion chamber of the unused means for burning the other fuel. Other objects will appear in the course of the ensuing description:

I attain these objects by the device illustrated, for example, in the accompanying drawing, in which—

Figure 1 is a perspective view of a grate for a cooking stove or range, in solid-fuel-burning position, part of one side of the 25 stove being also shown in connection with the holding means;

Fig. 2 is a similar view of the same grate in fluid-fuel-burning position;

Fig. 3 is a vertical front-to-rear section 30 of the fire-chamber of a cooking-stove with the grate of Figs. 1 and 2 therein, shown by solid lines in fluid-fuel-burning position, and by dotted lines in solid-fuel-burning position;

Fig. 4 is a similar vertical cross-section 35 of the same, parts being omitted for lack of space;

Fig. 5 is a sectional perspective view of a modified grate, suitable for a heating stove 40 or furnace having a round firepot, and embodying my invention; and

Fig. 6 is a perspective view of this grate of Fig. 5 constructed for cooking or laundry stoves or the like, wherein the fire-pot is 45 round.

As shown in Figs. 1 to 4, inclusive, the grate comprises a middle transverse bar 1 with fingers 2 branching from opposite sides thereof at right angles thereto, and the bar 50 1 and its fingers 2 are of approximately rectangular cross-section of ample area, similar to well-known grates of this type. One side 3 of the grid thus formed is substantially plane, as in any such grate. The 55 opposite side has on it, near opposite ends of

the grid, in its middle, the bellies or bulbs 4, extended from the otherwise substantially plane surface of this opposite side and substantially coextensive with the parts of the bar 1 and fingers 2 from which they extend. 60 As shown, each belly or bulb 4 is of general approximately circular outline, with the omissions from complete circular shape incident to the spaces between the fingers 2; so that each belly or bulb 4 comprises the middle part 5 along the bar 1, and middle longer branches 6 at opposite sides along respective opposite fingers 2 and shorter branches 7 from opposite ends of the middle part 5 along the adjacent fingers. These bellies or 70 bulbs 4 are thus shaped and located to lie approximately centrally under respective cooking-stove holes 8 (Fig. 4,) and are hollow throughout their middle parts 5 and branches 6 and 7, with all of their walls 75 except those formed by the grid bar 1 and fingers 2 of merely sufficient thickness to maintain their shape under the indirect heating influences existing under a solid-fuel-burning grate, while the bar 1 and fingers 2, 80 at these bellies or bulbs 4, are of substantially the same thickness as in other parts of the grid, to withstand the direct heating influences of the contacting burning solid fuel. The projected surfaces of these bellies or 85 bulbs 4 are substantially flat, and have a proper number of perforations 9 distributed substantially uniformly throughout these surfaces.

At opposite ends of the grid are arms or 90 trunnions 10 and 11, respectively, extending from the middles of the ends on the completely plane side of the grid, and inclining out away from the respective ends slightly, and then curving outwardly into substantially straight bearing parts 12 and 13, respectively; these parts 12 and 13 being in alinement on an axis substantially parallel with the center line of the grid. Each arm or trunnion 10 or 11 is hollow throughout its 95 length along the bearing part 12 or 13 and the connecting inclined part, and the interior of each arm or trunnion communicates with the interior of the respective belly or bulb 4 through a short junction part 14 or 15 100 running in along the middle of the grid from its respective end to the middle of the adjacent end of the respective bulb or belly 4.

All of the parts just described are preferably cast integral; the hollow interiors of 110

the bellies or bulbs 4 and the connecting arms or trunnions being formed by cores in the mold, as in any hollow casting.

The bearing parts 12 and 13 have their outer ends internally threaded, like pipe couplings. A nipple 16 is screwed into the part 12, and receives on its outer end an ordinary gas or fluid-fuel mixer 17. The nipple 18 comprises a reduced part 19 to screw into the threaded end of the other part 13, at the opposite end of the grate, and has oppositely radially extended arms 20 and 21, and a reduced part 22 at its outer end, receiving another mixer 23 like the mixer 17. One arm 20 is merely a handle; and the opposite arm 21 has an opening 24 through its outer end part, parallel with the grate axis. This nipple 18 and its arms 20 and 21 are preferably cast integral, with their openings cored. A knob 25, with a pin 26 projecting loosely through the opening 24, is fixed on the free end part of a flat spring 27 that has its opposite end part fixed to the arm 21 in close to the nipple 18, by a rivet 28, passed through the arm. The nipple 18 has its arms 20 and 21 close to its end part that is screwed into the bearing part 13.

A cooking-stove, such as is shown partly in Figs. 3 and 4, has suitable openings 29 made in its side plates 30, and alined openings 31 made in its linings 32 at the opposite ends of the fire-box; and small bores or holes 33 and 34 are made in the exterior of the plate 30 at one side, properly spaced from the opening 29 to receive the pin 26 when the grate bearing-part 13 is mounted in the opening 29 and the arm 21 is swung to either one of two positions diametrically opposite each other. The ordinary grate of the stove 40 is removed; these stoves usually having short grate fingers 35 at front and rear, and similar short grate fingers 36 at opposite ends, of the space occupied by the ordinary removable grate, which short fingers remain 45 fixed in the stove structure. The openings 29 and 31 in the stove plates and linings are at the right height from these remaining fingers to hold the grid of my improved grate substantially even with the fingers 35 and 36 when the parts 12 and 13 of the 50 grate arms or trunnions are bearing in the openings 29 and the grid is depending therefrom, as shown by the dotted lines in Figs. 3 and 4. The arms 20 and 21 and the threads 55 of the nipple reduced part 19 are preferably so related that the arms will stand substantially vertical when the grid is thus depending, with the holes 33 and 34 above and below the opening 29, and with the arm 21 60 up, so that its spring-carried pin 26 enters the upper hole 34, constituting a detent to hold the grate in its lowered position.

Fluid-fuel-supply pipes 37, one of which, at the left, is shown in Fig. 4, have valves 65 38 with nipples 39 loosely entering the outer

ends of the mixers 17 and 23; this being a common and practicable relation of these parts, since air is admitted around inflow of fluid fuel in the mixers, and the fuel-supply connection need not be fluid-tight. Thus, 70 rotation of the grate relative to the fuel-supply means is very convenient.

When the grate, mounted as above described, and properly proportioned as to width, so as to swing past the flanking fingers 75 35 at front and rear as indicated by the broken circle in Fig. 3, is swung upward through a half revolution, its side with the bellies or bulbs 4 is upward, and the perforated flat sides of these bellies or bulbs 4 80 are brought close to the stove-holes 8. It will be understood that the parts are so proportioned that these flat sides will be the correct distance down from the holes 8 when the grate is thus swung upward, and the 85 grid will be properly positioned relative to the grate-fingers 35 and 36 of the stove, when the grate is swung downward.

Thus, in lowered position, with its plane side up, the grid may be a practically identical substitute for the solid-fuel-burning grate part that was removed from the stove; and when the grid is elevated and inverted as a consequence, it presents its perforated bellies or bulbs under the respective cooking-stove holes 8, at the correct distance down therefrom to constitute thoroughly practical fluid-fuel burners, which are supplied with fluid fuel and air through their respective pipes, valves and mixers, in practically identically the same way as any well known and practicable fluid-fuel burner of the type required to be employed, whether for gas, either natural or artificial, or other fluid fuel, such as liquid fuel, in which case the 105 proper appliances can be as readily employed therewith as in any ordinary burner of that type, and any slight variations in design of the grate bellies or bulbs may be provided as are required in burners of that type. 110 Such details of design, and the necessary appliances for burning different kinds of gas or liquid fuel being well known to those skilled in the art, it is not deemed necessary to illustrate them in detail herein, or describe them further. In the example herein, the grate is constructed for gaseous fuel, and its supply connections arranged accordingly; and the application of its principle to other fuel-burning will be understood. 115

In any case, the maintenance of the practicable heavy design of the grate for burning solid fuels, such as coals of various kinds, or wood or other solid fuels, and the contaminant relation of the fluid-fuel burning 120 bellies or bulbs 4 to the required solid-fuel-burning grid elements, leaves the solid-fuel-burning grate-structure as fully open for free draft and escape of ashes and the like as in any practicable solid-fuel-burning 130

grate. Then, by inversion, the fluid-fuel-emitting perforations 9 are presented broad-side toward the surfaces to be heated, as the stove-lids 8' or any vessel that may be placed directly in the stove-holes 8 with the lids removed; and by virtue of the accompanying elevation of the grate during inversion, these perforations are brought within the required distance of the surfaces to be heated by the burning of the fluid fuel, which permits and requires operation at a much shorter range than solid fuels. Owing to the fluid-fuel-emitting perforations 9 being directed in substantially completely opposite direction from the solid-fuel-burning side of the grid, the entrance of ashes and the like to these perforations 9 during solid-fuel burning is practically eliminated.

Thus, the burning of either kind of fuel is accomplished in practically identically the same way, and under the same favorable conditions, as with an ordinary unconvertible grate or burner of the respective kind, without hindrance from the unused details in either instance. Inverting the grate for fluid-fuel burning is accomplished by merely withdrawing the pin 26 from the upper hole 34 and swinging the grate around half way and allowing the pin 26 to enter the lower hole 33. The handle arm 20 is provided to permit both hands to be used in swinging the grate from its lower solid-fuel-burning position in cases where the grid is somewhat firmly held by ashes and the like wedged between it and the stove parts, as the fixed fingers 35 and 36 of the stove; it not being necessary to carefully clean out the fire-box of the stove to make the change for burning fluid fuel. Likewise, in swinging the grate down from fluid-fuel-burning position to burn solid fuel again, the handles constituted by the two opposite arms 20 and 21 will afford ample leverage for forcing the grid down into position against any ashes or other obstacles happening to lie in the grate space.

The integral bearing parts 12 and 13, extended out for enough to receive their threaded connections well outside the linings of the stove, avoid warping or fusing of the connections; which latter are provided, making the fuel-supply connections detachable, to facilitate insertion of the device into stoves already assembled and in use, and which should be as readily detachable when it is desired to remove the grate from the stove after considerable use, for renewal, repairs, or other reasons. The grate with such detachable connections is thus adapted to have the connections removed for insertion or removal of the grate through the top of the stove, after which the connections are inserted and screwed in place, or unscrewed and withdrawn, from the respective sides of the stove, through

the bearing openings; or, preferably, as here shown, the bearing parts, as their name implies, being extended outside the bearing openings and receiving the connections directly, outside the stove.

Those parts of the grate arms or trunnions 10 and 11 that must lie inside the stove linings, exposed to direct contact with the burning solid fuel, as at 40 and 41 in Fig. 4, are properly thickened, preferably by placing the cores eccentrically in the mold spaces, when the grate is cast. This is in accordance with the principle of my invention to make all parts of the grate exposed to live coals or fire bed amply heavy to resist warping, fusing and burning, to as full an extent as is provided for in any ordinary solid-fuel-burning grate; and at the same time to have the entire grate no heavier than is necessary, not only in the interest of economy of construction and ease of handling, but, in the fluid-fuel-burning parts, to have the walls that are perforated as thin as they should be to constitute the perforations proper fluid-fuel-burner exits. It is by the arrangement, substantially as herein exemplified, that all of these provisions can be met to the full practicable degree.

In the modification of Fig. 5, and also in Fig. 6, the grate comprises a central core-ring 42, with its opening upright therethrough, of ample draft and ash-dropping capacity, with bars 43 radiating therefrom to a rim 44, leaving sector-shaped openings 45 between the bars 43, also amply spaced. The belly or bulb 4' is projected from the core-ring 42 and adjacent parts of the arms or bars 43, being substantially coextensive therewith, and is hollow, with the perforations 9' in its flat face. In Fig. 5, the arms or trunnions 10' and 11' are simply straight and the former is solid, while the latter, 11', is hollow, communicating with the hollow interior of the belly or bulb 4', and has its outer end internally threaded, at 46. It is thus adapted to receive a nipple for connection with a mixer, and the nipple may have suitable manipulating and detent means, like the nipple 18 of the preceding example. There being only one belly or bulb, or fluid-fuel burner, this one connection is sufficient, and the opposite trunnion 10' may be solid, as just described. This example of Fig. 5 is for stoves or furnaces intended only for heating the surrounding spaces, and not for cooking or other purposes requiring raising of the fluid-fuel-burning parts on inversion; hence the arms or trunnions 10' and 11' need not be curved or inclined as in the preceding example.

In Fig. 6, however, this grate, otherwise as shown in Fig. 5, and as just described, has its arms or trunnions 10'' and 11'' curved and inclined, with bearing parts 12'' and 13'' having the functions of the first

described example, except that the former, 10", may be solid; the opposite one having the outer end of its part 13" internally threaded, to receive a nipple such as the 5 nipple 18, and the grate being installed and operated substantially as was described for the first example. Such a round grate, with provision for elevation and depression incident to inversion, is useful in stoves of the 10 cooking-stove type which have round fire-pots, as for instance some kinds of laundry stoves. It will be understood that in either of the round-grate examples, in Fig. 5 or Fig. 6, the different parts are made proportionately heavy and light, to afford the best 15 solid-fuel and fluid-fuel burning properties, as was fully described for the first example. Also, grates of other shapes, either with or without the plural fluid-fuel burner arrangement, or with or without the provision 20 for raising and lowering incident to inversion, may be provided according to my invention; and other variations in the details of construction may be made under certain 25 conditions that may arise. Accordingly, while certain constructional details are deemed preferable in connection with my invention, and I have shown and described these rather specifically in elucidating the 30 construction and use of my invention, as is required, I do not wish to be understood as being limited to such precise showing and description of any of the given examples, but having thus fully described my invention, 35 what I claim as new and desire to secure by Letters Patent is:

1. In a grate, the combination of a grid comprising a plurality of elements, each of solid-fuel-heat resisting depth and ash-discharging width, with spaces of ash-discharging width respectively between each two adjacent elements, said grid having its opposite faces substantially in parallel respective planes, a hollow part on one face 40 of said grid, projected outside the plane of said face and confined substantially between the adjacent spaces of the grid, and having perforations leading out from its hollow interior substantially perpendicularly to said 45 plane, means whereby said grid is adapted to be raised with said hollow part facing upwardly or lowered with said hollow part facing downwardly and a fuel-inlet for said hollow part.
2. In a grate, a grid having a fluid-fuel-burning part and an opposite solid-fuel-burning face, means whereby said grid is adapted to be raised with said fluid-fuel-burning part facing upwardly, or lowered 50 with said fluid-fuel-burning part facing downwardly, and a fuel-inlet for said fluid-fuel-burning part.
3. In a grate, a grid having a fluid-fuel-burning part and an opposite solid-fuel-burning face, supporting members on said 55

grid, projected outside the plane of said opposite face of the grid, one of said members being a fuel-inlet to said fluid-fuel-burning part, and detent means on one of said members to engage with a stove or furnace part 70 and hold said grid either in a raised or a lowered position by means of said members.

4. In a grate, a grid having fluid-fuel-burning parts near opposite ends thereof and an opposite solid-fuel-burning face, supporting members on said grid, projected outside the plane of said opposite face of the grid, each one of said members being a fuel-inlet to a respective adjacent fluid-fuel-burning part, and detent means on one of said 75 members to engage with a stove or furnace part and hold said grid either in a raised or a lowered position by means of said members.

5. In a grate, a grid having a fluid-fuel-burning part and an opposite solid-fuel-burning face, supporting means for said grid on which said grid is reversible, an arm on said supporting means, and a spring-pressed member on said arm, to engage with either one of two parts of a stove or furnace, 80 to hold said grid in either one of two positions.

6. In a grate, a grid having a fluid-fuel-burning part and an opposite solid-fuel-burning face, supporting means whereby said grid is adapted to be raised with said fluid-fuel-burning part facing upwardly, or lowered with said fluid-fuel-burning part facing downwardly, a fluid-fuel inlet for 90 said fluid-fuel-burning part, and means for fastening said grid in its raised or its lowered position.

7. In a grate, a grid having a fluid-fuel-burning part and an opposite solid-fuel-burning face, supporting members on said grid, projected outside the plane of said opposite face of said grid, one of said members being a fuel-inlet to said fluid-fuel-burning part and having its outer end part 105 threaded, and a nipple screwed to said threaded part for extension to suitable fuel-supply means.

8. In a grate, a grid having a fluid-fuel-burning part and an opposite solid-fuel-burning face, supporting members on said grid, projected outside the plane of said opposite face of said grid, one of said members being a fuel-inlet to said fluid-fuel-burning part and having its outer end part 115 threaded, a nipple screwed to said threaded part for extension to suitable fuel-supply means, and means on said nipple to engage with either one of two parts of a stove or furnace, to hold said grid in either one of 120 two positions into which it may be moved by means of said supporting members.

9. A reversible grate comprising a plurality of elements, each of solid-fuel-heat resisting depth and ash-discharging width, 130

with spaces of ash-discharging width respectively between each two adjacent elements, said grate having its opposite faces substantially in parallel respective planes, a 5 hollow part on one face of said grate, projected outside the plane of said face and confined substantially between the adjacent spaces of the grate, and having perforations leading out from its hollow interior substantially perpendicularly to said plane, and 10 means for admitting fuel to said hollow part.

10. A reversible grate comprising a grid element with a solid-fuel-supporting face and a fluid-fuel-conducting cavity at a solid-fuel-heat resisting depth below said face, 15 with perforations leading from said cavity out through the extreme opposite face of said element, means for admitting fluid fuel to said cavity, and means for raising said 20 grate with said perforations upward, or lowering said grate with said solid-fuel-supporting face upward.

CHARLES J. TRAUB.
